ELECTRODE STRUCTURE

Charles M. Gove, Bound Brook, N. J., assignor to
Research Corporation, New York, N. Y., a cor-
poration of New York

Application April 1, 1939, Serial No. 265,531

14 Claims.

(Cl. 183—7)

This invention relates to the electrical treatment of fluids and is particularly directed to improvements in discharge electrode structures for Cottrell electrical precipitators.

5 A principal purpose of the invention is the provision of discharge electrode structures whereby the corona discharge may be controlled.

10 A further purpose of the invention is the provision of means for balancing and controlling the corona discharge from all portions of a discharge electrode structure to produce maximum precipitating effect upon suspended particles.

15 Another purpose of the invention is the provision of an electrode structure which will provide a maximum of corona discharge with a relatively low voltage.

20 Still another purpose of the invention is the provision of an electrode structure the discharge characteristics of which may be readily altered to suit varying operating conditions independent 25 of changes in the voltage or other characteristics of the potential supplied thereto.

Other objects and advantages of the invention will be apparent from the following discussion.

25 Electrode structures providing a high corona discharge at relatively low voltages by the use of very fine wires or sharp points having small radii of curvature are known in the art. However, the known structures suffer from a number 30 of disadvantages. The voltage at which corona discharge appears tends to decrease with decreasing radius of curvature of the electrode structure, but when using fine wires or points the decreasing stiffness of the wires or points requires the 35 use of supporting members, which introduce disadvantageous complications due in part to the shielding effect of such members on the corona emitting portions and in part to the disturbing effect of extended surfaces of low radius of curvature on the field distribution.

40 These disadvantages are avoided in the present invention by the provision of electrode structures including supporting members of relatively large radius of curvature and corona discharge elements of relatively small radius of curvature, supported by said supporting members adjacent to but spaced from substantially all the extended surfaces of the supporting members, for example, by helically disposed helices of fine wire about 45 the supporting members.

45 The distance the corona discharging element extends out from the supporting surface may be varied within limits to regulate the amount of corona discharge. When this distance is less 50 than $\frac{1}{8}$ inch the reduction in corona current

flow is very substantial, while when the distance is greater than $\frac{3}{8}$ inch the change in corona current flow with changes in the distance is relatively small.

5 In general, it is desirable that the corona forming elements should have a radius of curvature not exceeding about 0.5 millimeter or 0.02 inch and that they should project at least 10 millimeters from the extended surface of the supporting member.

10 A particularly advantageous structure is provided by loosely coiling a flexible, but preferably non-resilient, helical coil of wire about a stiff self-supporting conductive member. The discharge properties of this structure may readily be 15 controlled by suitably selecting the diameter of the wire of which the coil is made and the pitch and diameter of the coil.

20 The invention will be described in further detail for the purpose of illustration with reference to the accompanying drawings in which:

Fig. 1 is a sectional elevation of a vertical flow electrical precipitator embodying the principles of the invention;

25 Fig. 2 is an elevation in partial section taken at right angle to the view of Fig. 1;

Fig. 3 is an enlarged detail of a discharge electrode structure of the invention; and

30 Fig. 4 is an elevation in partial section of a pipe precipitator embodying the invention.

In Figs. 1 and 2, 10 is the shell of a precipitating chamber having inlet, or outlet, 11 and outlet, or inlet, 12, and provided with spray devices 21 in the upper portion. The chamber is provided with a plurality of parallel plate collecting electrodes 13 supported from and in electrical contact with the grounded shell 10. Between the collecting electrodes 13 are provided a plurality of discharge electrode structures comprising frame members 14, 14'. Upper frame member 14 is supported upon beams 15 carried by insulators 16 housed in heated insulator housings 17. The discharge electrode structure is energized by conductor 18 leading from a source of potential, not shown, through one of the insulators 16.

35 A plurality of attenuated discharge elements, for example, metallic wires 19, are suspended between the upper and lower frame members. Helically coiled about the frame members of the discharge electrode structure are wire coils 20 providing discharge elements.

40 The relation of the members 20 to the supporting elements 14, 14' is shown more clearly in Fig. 3. From this figure it may be seen that the outer portions of the members 20 provide a se- 45

- ries of discharge points or attenuated elements 20' spaced from the support a distance governed by the diameter of the coil and spaced from each other a distance governed by the pitch of the coil.
- 5 The coils are attached to the support at convenient points, for example, by welding. The wire is preferably non-resilient, so that the coils tend to retain their positions on the supports in spite of accidental breaking of the wire.
- 10 The discharge electrodes of Figs. 1 and 2 will be seen to comprise a plurality of attenuated discharge members, members having relatively extended surfaces from which the attenuated discharge elements are suspended, and further 15 attenuated elements disposed adjacent the extended surfaces of the supporting members whereby a controlled corona discharge may be obtained in the areas adjacent the supporting members as well as adjacent the attenuated discharge elements supported thereby. In this way, "dead" areas, in which no precipitation occurs or in which precipitation may even occur 20 on portions of the discharge electrode system, are eliminated.
- 25 The precipitator of Fig. 4 consists of a shell 40 having spray devices 41 in the upper portion thereof and provided with inlet 42 and outlet 43. Passing through and supported by horizontal partition 44 are a plurality of vertical 30 pipes 45 which are in electrical connection with the grounded shell 40 and form collecting electrodes.

Axially supported in each of the collecting electrode pipes is a discharge electrode structure comprising a stiff supporting member 46 and an attenuated discharge member 47 providing elements of small radius of curvature spaced from the surface of the supporting member. The discharge electrode structure is advantageously formed of a coil of wire helically wound about the supporting member, as shown in detail in Fig. 3.

The supporting members 46 of the discharge electrode are carried by beams 48 which are suspended in horizontal position in the lower part of the precipitator from insulators 49 through one of which the electrodes are connected to a high potential source, not shown, by conductor 50. Passage of liquid along the beams into the insulator chambers 51 is prevented by pipe sections 52 mounted on the beams and sloping toward the interior of the precipitator.

55 The discharge electrode structure of this precipitator combines simplicity and economy of production on the one hand with ready adaptability to a wide range of operating conditions on the other and permits the discharge characteristics of an electrical precipitator to be varied over a wide range at a negligible cost. A considerable variation can be obtained by merely altering the pitch at which the wire coil is wound about the supporting member, and much more 60 extensive variations can be provided at very small cost by replacing the coil with coils having different wire diameter, coil diameter or coil pitch.

I claim:

- 70 1. A discharge electrode structure comprising an electrically conductive supporting member of relatively large radius of curvature and a flexible corona discharge forming member supported thereby comprising a wire coil in contact with 75 said supporting member with the axis of the

coil helically disposed about said supporting member.

2. A discharge electrode structure comprising an electrically conductive supporting member of relatively large radius of curvature and a flexible corona discharge forming member supported thereby comprising a wire coil having its axis helically disposed about said supporting member and being in tangential contact with said supporting member at a plurality of points 10 spaced along a helical path on the surface of the supporting member.

3. A discharge electrode structure comprising an electrically conductive supporting member of relatively large radius of curvature and a flexible corona discharge forming member supported thereby comprising a wire coil in contact with said supporting member with the axis of the coil helically disposed about said supporting member the diameter of said coil being sufficient to space the outermost portions of the convolutions thereof a sufficient distance from the surface of the supporting member to substantially eliminate the shielding effect thereof.

4. A discharge electrode structure comprising an electrically conductive supporting member of relatively large radius of curvature and a flexible corona discharge forming member supported thereby comprising a wire coil in contact with said supporting member with the axis of the coil 20 helically disposed about said supporting member, the diameter of said coil being at least $\frac{1}{8}$ inch.

5. A discharge electrode structure comprising an electrically conductive supporting member of relatively large radius of curvature and a flexible corona discharge forming member supported thereby comprising a wire coil in contact with said supporting member with the axis of the coil helically disposed about said supporting member, the wire of said coil having a radius not exceeding about 0.02 inch.

6. A discharge electrode structure comprising an electrically conductive supporting member of relatively large radius of curvature and a flexible corona discharge forming member supported thereby comprising a wire coil in contact with said supporting member with the axis of the coil helically disposed about said supporting member, the wire of said coil having a radius not exceeding about 0.02 inch and the diameter of said coil being at least $\frac{1}{8}$ inch.

7. A discharge electrode structure comprising an electrically conductive supporting member of relatively large radius of curvature and a flexible corona discharge forming member supported thereby comprising a coil of non-resilient wire in contact with said supporting member with the axis of the coil helically disposed about said supporting member.

8. In an electrical precipitator for the removal of suspended particles from gases, a collecting electrode and a discharge electrode structure comprising a plurality of extended surface supporting members, a plurality of corona discharge forming elements supported in spaced relation to said collecting electrode by said supporting members, and a plurality of corona discharge forming elements distributed over the extended surface of said supporting members, 70 said last named elements having a radius of curvature not exceeding 0.02 inch and extending from said supporting surface member at least $\frac{1}{8}$ inch and not more than $\frac{3}{8}$ inch.

9. In an electrical precipitator for the removal 75

- of suspended particles from gases, a collecting electrode and a discharge electrode structure comprising a plurality of extended surface supporting members, a plurality of corona discharge forming elements supported in spaced relation to said collecting electrode by said supporting members, and a plurality of corona discharge forming elements distributed over the extended surface of said supporting members, said last named elements being provided by a coil of wire in contact with said supporting member, with the axis of the coil helically disposed about said supporting member.
10. In an electrical precipitator for the removal of suspended particles from gases, a collecting electrode and a discharge electrode structure comprising a plurality of extended surface supporting members, a plurality of corona discharge forming elements supported in spaced relation to said collecting electrode by said supporting members, and a plurality of corona discharge forming elements distributed over the extended surface of said supporting members, said last named elements being provided by a coil of wire in contact with said supporting member with the axis of the coil helically disposed about said supporting member, the diameter of said coil being at least $\frac{1}{8}$ inch.
11. In an electrical precipitator for the removal of suspended particles from gases, a collecting electrode and a discharge electrode structure comprising a plurality of extended surface supporting members, a plurality of corona discharge forming elements supported in spaced relation to said collecting electrode by said supporting members, and a plurality of corona discharge forming elements distributed over the extended surface of said supporting members, said last named elements being provided by a coil of wire in contact with said supporting member with the axis of the coil helically disposed about said supporting member, the wire of said coil having a radius not exceeding about 0.02 inch.
12. In an electrical precipitator for the removal of suspended particles from gases, a collecting electrode and a discharge electrode structure comprising a plurality of extended surface supporting members, a plurality of corona discharge forming elements supported in spaced relation to said collecting electrode by said sup-
- porting members, and a plurality of corona discharge forming elements distributed over the extended surface of said supporting members, said last named elements being provided by a coil of wire in contact with said supporting member with the axis of the coil helically disposed about said supporting member, the wire of said coil having a radius not exceeding about 0.02 inch.
13. In an electrical precipitator for the removal of suspended particles from gases, a collecting electrode structure and a discharge electrode structure spaced from and electrically insulated from said collecting electrode structure and enveloped thereby on at least two sides, the discharge electrode structure comprising an extended surface supporting member, a plurality of corona discharge forming elements distributed over the surface of said member and a plurality of corona discharge forming elements depending from said member, said corona discharge forming elements being positioned and shaped to produce when energized substantially uniform precipitating effect from all portions of the discharge electrode structure to the surfaces of the collecting electrode structure.
14. In an electrical precipitator for the removal of suspended particles from gases, a collecting electrode structure and a discharge electrode structure spaced from and electrically insulated from said collecting electrode structure and enveloped thereby on at least two sides, the discharge electrode structure comprising an extended surface supporting member, a plurality of corona discharge forming elements distributed over the surface of said member and a plurality of corona discharge forming elements depending from said member, the corona discharge forming elements distributed over the surface of said extended surface supporting member being spaced and shaped to provide when energized a precipitating effect from said member to the collecting electrode structure substantially equivalent to the precipitating effect from said depending corona discharge forming elements to said collecting electrode members.
